DRIVE FOR JACQUARDS FOR TERRY LOOMS

Herbert V. Foster, Providence, R. I., assignor to
Crompton & Knowles Jacquard & Supply Com-
pany, Pawtucket, R. I., a corporation of Massa-
chusetts

Application June 17, 1939, Serial No. 279,698

8 Claims. (Cl. 139—59)

This invention relates to improvements in jac-
quard mechanism for looms and it is the general
object of the invention to provide a jacquard
more particularly adapted for the weaving of
5 terry fabrics having figured patterns.

In weaving so-called three pick terry fabrics
three beats of the lay are required to complete
one row of tufts across the cloth. The weft is
held in a rearward position for the first two picks
10 and then is given a full forward motion with
the third pick, the pile warp lying between the
picks and the preceding row of tufts being looped
when all three picks are beaten up. The loom
therefore operates on a three-pick cycle.

When the pile warps and the loops formed
from them are controlled so as to produce a
fancy pattern it has been customary heretofore
to have a separate card on the jacquard for each
20 pick of the loom, necessitating three cards for
one row of terry tufts. It is an important object
of my present invention to economize on the
cards by providing a jacquard so constructed and
operated that one card will suffice for the three
25 picks for each row of tufts.

In my co-pending application Serial No. 222,184
I set forth a jacquard which accomplishes the
foregoing results by the use of cams for raising
the knives of the jacquard in such an order that
30 at any instant in the jacquard operation one
knife will be rising, the second knife will be de-
scending, and the third knife will be dwelling
in low position, each knife in its turn at three-
pick intervals rising for one pick, then falling
35 for one pick, and thereafter remaining down for
one pick. In my aforesaid application I claim
broadly means for giving the knives the sequence
of movements just described, but I have found
that under some conditions of jacquard opera-
40 tion a set of cranks possesses certain advantages
over the cams, such for instance as speed of op-
eration, and it is a further object of my present
invention to effect the advantages set forth in
that application by means of cranks instead of
45 cams. The cranks give a continuous motion to
certain jacquard parts and this I believe con-
tributes to the higher speed attainable by their
use.

In the description which follows I have set
50 forth certain parts of my invention as disclosed
in the aforesaid application together with the
group of cranks which effect the knife move-
ments.

With these and other objects in view which will
55 appear as the description proceeds, my invention

resides in the combination and arrangement of
parts hereinafter described and set forth.

In the accompanying drawings, wherein a con-
venient embodiment of my invention is set forth,

Fig. 1 is a side elevation of the upper part of
a loom having attached thereto a jacquard made
according to my present invention,

Fig. 2 is an enlargement of a portion of the
upper part of Fig. 1, showing the cylinder oper-
ating mechanism,

Fig. 3 is an enlarged side elevation of the
upper part of Fig. 1, with the sprocket wheel
removed,

Fig. 4 is a detailed section on line 4—4 of
Fig. 3,

Fig. 5 is an end view taken in the direction
of arrow 5, Fig. 3,

Fig. 6 is a plan view taken in the direction of
arrow 6, Fig. 3,

Fig. 7 is a horizontal section on line 7—7, 20
Fig. 3,

Fig. 8 is a diagrammatic view of a weave when
the pattern effect is obtained by reversing the
location of colored tuft warps from one side to
the other side of the fabric,

Fig. 9 is a diagrammatic cross section of the
fabric made according to the weave set forth in
Fig. 8 after the tufts have been beaten up,

Fig. 10 is a diagrammatic view of a weave in
which the patterned effect is obtained by throw-
30 ing all of the figured terry warps on one side of
the cloth,

Fig. 11 is a view similar to Fig. 9 but showing
the fabric made according to the weave set forth
in Fig. 10,

Figs. 12 to 15 are diagrammatic views showing
the successive steps in forming a row of terry
tufts,

Figs. 16 and 17 show two sets of cards punched
to produce the weaves shown in Figs. 8 and 10, 40
respectively,

Fig. 18 is a diagrammatic view showing the
relation of the knives, pairs of jacks, jacquard
cylinder and cards, and the lifter cords, two
needles entering holes in a card and two being 45
pushed back by blank places on the card, and

Fig. 19 is a graph showing the relation of the
crank motions and the support for the warp lifter
jacks.

In order that the invention may be more read-
ily understood I will first describe the types of
patterned terry fabrics set forth in Figs. 8 and
10. For convenience in illustrating the weave I
have shown the picks of filling separated in
groups of three, the groups being indicated at I 55

to VII, inclusive, and the picks of each group being indicated at *a*, *b*, and *c*, in the order in which they are laid by the shuttle. It is to be understood that there are two different sets of warp threads in terry fabrics, the first of which forms the ground weave and is tight throughout the weaving of the fabric, while the second set is slackened periodically at three-pick intervals to permit the formation of tuft piles. Each of these sets of warp threads is interwoven with the picks of filling, the ground warps having always the same relation with respect to the filling and undergoing no change when the pattern is formed, while the terry set will also sustain the same relationship to the picks of filling while unpatterned terry is being woven, but the terry warps change their relationship with respect to the picks of filling at the beginning and ending of a patterned figure. The relation of the terry warps with respect to the picks of filling will be unchanged throughout the weaving of the figures. The jacquard to be described herein-after controls the terry warps and the usual cam harness mechanism not shown is employed for the weaving of the ground warps.

Referring to Fig. 8, the terry warps 25 and 26 are represented at the left hand of the figure as at the top and bottom, respectively, of the shot of filling Ia. In this type of weave the terry warps 30 may be of different colors, the warp 25 passing under shot Ib and over shot Ic. The lower warp 26 has the opposite relation with respect to these shots and leaves the group I under the warp 25. The space between shots Ic and IIa represents 35 the length of terry warp which is to make the tufts pile. That part of the weave already described constitutes a normal non-patterned part of the fabric before the patterned area is reached.

When the location of the terry warps is to be 40 reversed the relation will be that shown in group III. The relation of terry warps in this group will be the reverse of that shown in group I, the upper warp 25 passing under shot IIIa, after which its relationship with respect to the shots 45 of filling in group III will be as indicated, the length of terry warp 25 between shot IIIc and IVa from which the terry tuft is formed being now on the under side of the fabric. In a similar manner the terry warp 26 is on the top of the 50 fabric. The interweaving of the groups IV and V will be similar to that of group III, and it is to be understood that there will be as many groups similar to IV and V as are required by the figure being woven.

55 When the terry 25 is to be returned to the top of the fabric the relationship will be that shown in group VI where warp 25 is raised to lie over shot VIa, this marking the end of the pattern figure, after which the relation between the shots 60 of filling and the two sets of terry warps will be the same as that described for the group I. When all the loops are formed in the fabric they will appear as suggested in Fig. 9, where the two upper left hand tufts are formed from warp 25, 65 the next upper three reading to the right being formed of warp 26, while the remainder of the upper tufts are again formed of the set 25. The reverse pattern effect appears on the bottom of the cloth.

70 Referring to Fig. 10, the upper and lower terry warp threads 27 and 28 at the left hand end sustain the same relation to the shots of group I and II as in the previous weave, but in this instance the set 28 remains unchanged throughout the 75 weaving of the pattern, being the same for both

the body and pattern, the warp 28 passing over the center shot of each group and under the other two. The warp 28 is therefore not necessarily controlled by the jacquard since it has a simple invariable three-shot cycle, and a three 5 pick cycle cam harness mechanism as commonly used may be employed.

The other warp 27, however, is changed so that at times it is on the upper part of the fabric, as suggested at the left and right hand ends of Fig. 10, and at other times parallels the warp 28 to form the pattern as suggested in the intermediate part of Fig. 10. Under these conditions warp 27 will be controlled as is warp 25.

The fabric produced by the weave shown in Fig. 10 is set forth in Fig. 11 where the right and left hand ends of the fabric have piles on both sides, whereas the intermediate portion has all of the piles thrown to the under side, the upper part being blank to form the pattern.

20 It will be seen by referring to Figs. 8 and 10 that the upper set of warps starting at the left hand end indicated at 25 and 27 undergo a change when the pattern is reached and also when it is concluded and that in Fig. 8 the lower warp 26 has a similar but opposite relationship. In order to simplify the description the mechanism will be described as though it were to weave the fabric shown in Fig. 10, but it will be understood that the jacquard cards can be punched 30 to produce the weave of Fig. 8, as will be set forth herein-after.

25 Referring more particularly to Fig. 1, I have shown a loom frame 30 having a lay 31 and a reed 32 which is given two relative settings with 35 respect to the lay by means of mechanism such as that shown in Patent No. 2,082,883. This mechanism is well known and is thought to need no further description other than to say that the first two picks of a cycle are beaten up to a position behind the fell, as in Fig. 13, while the third pick is beaten up to the first two as in Fig. 14, and then on the same beat all three shots are beaten to the fell of a cloth, thereby bending the terry warps to form tufts as in Fig. 15. The lay 40 may be driven by the usual connector 33 actuated by the top or crank shaft 34 of the loom.

The jacquard J comprises cross timbers 35 mounted on uprights 36 supported from the floor and has a frame 37. I provide three sets of 50 vertically reciprocating knives indicated at 41, 42 and 43, each set comprising several knives which move together. The knives 41 are carried by a rack 45 which is raised and lowered by links 51 55 adjustably connected to a vertically rocking lever 61.

The lever 61 is connected by rod 74 to a crank rotated by shaft 46 journaled in an auxiliary frame 40 on the timbers. Knives 42 are carried by a rack 47 connected by links 52 to lever 62 60 which is connected by rod 75 to a second crank 12 also rotated by shaft 46. The third set of knives 43 is mounted on the third rack 48 which is vertically reciprocated by links 53 connected to driving lever 63 which in turn is connected by rod 76 to a third crank 73 also rotated by shaft 46. The cranks will be described in more detail presently in connection with Figs. 3 and 5. Vertical guide rods 49 are provided for the several racks and supported by frame 37 to require the knives 65 to move vertically in fixed paths as the cranks rotate.

The cranks 71, 72 and 73 are all driven by shaft 46 in equiangular relationship, adjacent cranks being spaced apart by an angle of 120° around the 75

axis of shaft 46. Crank 73 is set-screwed to shaft 46, see Fig. 5, and has a wrist pin 73a, see Fig. 3, for adjustable head 56 on rod 76. Secured to the pin 73a is a plate 73b which is fastened to a second plate 72b carrying a wrist pin 72a for the adjustable head or rod 75 and similar to head 56. Pin 72a is secured to a plate 72c attached to plate 71b, and the latter carries a third wrist pin 71a for the adjustable head at the bottom of rod 74. Pin 71a is secured to a crank 71 set-screwed on a stub shaft 46a carried by an auxiliary bearing 46b, see Fig. 5. Plates 72b and 72c may be considered as forming cranks 72, while the parts set-screwed to shafts 46 and 46a constitute the crank 73 and 71, respectively. Stub shaft 46a is coaxial with shaft 46, and all the cranks turn about the axis common to these two shafts. Slots 69 in the cranks and plates permit variation of the amount of motion to be imparted to levers 61, 62 and 63.

Rotation of shaft 46 is accomplished by the mechanism shown in Fig. 1 which includes a sprocket gear 65 fastened to the shaft 46 and driven by a chain 66 trained around a sprocket 77 fast on crank or top shaft 34. Sprocket 65 is three times the diameter of sprocket 77, so that shaft 46 is given one complete rotation for each three rotations of the shaft 34, or picks of the loom.

30 The card cylinder is operated by a cam 90 secured to shaft 46 and having a groove 91 to receive roll 92 on lever 93 fulcrumed at 50. A bell crank lever 95 moving about a fixed axis 96 has driving connection with lever 93 through an adjustable link 97 and in turn is connected by a second link 98 to a driving head 99 adjustably secured to a rod 100 slidably horizontally on the jacquard frame. The outer end of the rod 100 has secured thereto a cylinder support indicated generally at 101 for supporting rotatably thereon the jacquard cylinder 102. An operating pawl 103, Fig. 3, pivoted at 104 to the jacquard frame has a hooked head 105 to engage successively the several pins 106 formed in the corners of the cylinder at one end. The matter just described is of common construction and except for the cam 90 may be made according to accepted practice.

As shown in Fig. 2 cam 90 has two low points 110 and 111 with a high intermediate run 112 connecting these points on one side of the shaft 46 and a still higher run 113 on the opposite side of the shaft. When the roll 92 approaches one of the low points the parts are rocked in such a direction as to move the cylinder 102 to the left or in toward the needles 115 and when run 112 is occupied by the roll 92 the cylinder is moved away from the needles a slight amount not sufficient however to cause engagement of the pawl 103 with one of the pins 106. As the cam moves in the direction of the arrow Fig. 2, the other low point then operates to move the cylinder back toward the needles, after which the high run 113 comes into play to move the cylinder at its maximum distance away from the needles and cause turning of the cylinder by the pawl 103 in well-known manner to present a new pattern surface.

The cylinder has trained thereover a series of jacquard cards C', C2, C3, etc., which are presented to the needles one at a time every third pick of the loom by the mechanism just described and shown in Fig. 2. These cards are shown in more detail in Figs. 16 and 17.

75 Fig. 18 shows four needles each controlling a

pair of jacks together with four sets of knives. It will be understood that the jacquard will have a number of needles and pairs of jacks depending upon the number of terry warps to be controlled, but this description will be limited to the 5 needle and jacks which control the terry warps of one longitudinal row of terry tufts, it being understood that the remaining needles and jacks will operate in a similar manner.

As shown in Fig. 18 each group of three knives 10 is associated with two upright jacks 118 and 119, the first jack having a hook 121 for engagement with knife 41 while the second jack 119 has hooks 122 and 123 for engagement with knives 42 and 43 respectively. The hooks 122 15 and 123 point in opposite directions and are so related that when one of them lies in the path of the knife corresponding thereto the other hook will be out of the path of its knife so that but one of the knives 42 or 43 is able to lift jack 20 119 at a time.

The lower end of each jack is provided with a supporting hook 125 which rests on a stationary plate 126 carried by the jacquard frame, and a link 127 connects the bottoms of the two 25 jacks to a terry warp lifter cord 128. When one of the jacks is raised the link 127 moves upwardly therewith to elevate the cord 128 and slides along the bent lower part 129 of the unraised jack, but when both jacks are down the lifter cord 30 and terry warp controlled thereby are in low position.

Each needle 115 has a pair of loops 130 by which it controls the pair of jacks 118 and 119 and has the usual spring 131 to hold the needle 35 in normal out position with the hooks 121 and 123 in the paths of their knives 41 and 43, respectively, while hook 122 will be out of the path of its knife 42. This relation is shown at the right hand pair of jacks in Fig. 18. When the 40 needle is pushed in or moved to the left as viewed in Fig. 18 both jacks controlled thereby change their relative position with respect to the associated knife, hooks 121 and 123 moving clear of their knives while hook 122 is placed over its 45 knife 42. This relation is shown in the left hand pair of jacks 116 and 117, Fig. 18.

Before continuing the description of Fig. 18 I will describe the nature of the knife motions and the jacks 118 and 119. The graph shown 50 in Fig. 19 represents the character and time of motions of the knives and the lifter jacks and the part played by the support 126 in maintaining the jacks in low position for one pick of the cycle. In Fig. 19 the three sinusoidal curves 55 L, M and N represent the rising and falling motions of the knives 41, 42 and 43, respectively, and the mid-line RS represents time or degrees of loom crank shaft motion. The knives are moved by the cranks shown in Fig. 3 and because of the fact that these three cranks are spaced equally around the shaft 46 the curves L, M and N will be separated by one pick or 360° of loom time. It should be borne in mind that the reversal effected by the levers 61, 62 and 63 65 means that an up motion of the knives and the curves in Fig. 19 correspond to a down motion of the cranks.

Considering curve L and knife 41 to which it corresponds, the knife will rise on one pick of a 70 loom to reach a high position indicated at 202 in Fig. 19, after which it will descend to low point 203. Since it is necessary to have a dwell of the jacks in low position for one pick it is necessary to provide for an idle motion of knife 41 75

for a period of approximately one pick or 360° of loom time. This dwell of the jacks in low position is caused by the support 126 shown in Fig. 18. This support is fixed on the jacquard and so located that when the warp thread is all the way down, or in the bottom shed, the hook 125 will engage the support 126 to prevent further descent of the jack. In Fig. 19 the dashed line 126a corresponds to the location of the support 126 and the points of crossing between curve L and line 126a, indicated at 204 and 205 are approximately one pick apart. From this it will be seen that although knife 41 continues to move in the lower part of its range of motion, it does so while out of supporting relation with respect to the jacks and it is for this reason that the dwell of the jack in low position for one pick is accomplished.

In a similar manner, knife 42 will have a motion as indicated by curve M, and since it is one pick later than curve L, knife 42 when descending will deposit a jack on support 126 at about the same time that ascending knife 41 can start to lift the jack previously held in low position by the support 126. Likewise curve N corresponds to the motion of knife 43.

It will be seen from Fig. 19 that each of the three curves L, M and N has a portion thereof which dips below the line 126a and that the dippings below this line are approximately one pick apart, and further that each curve remains below line 126a for approximately a pick of the loom. By the relation shown in Fig. 19 knife 41 and any jack held thereby will have reached the high point 202 and will start down at approximately the same time that knife 42 in its up motion can engage another jack to start lifting the same, this point being represented at 206 in the graph. This same relation exists also between knives 42 and 43 and later between knife 43 and knife 41 for the beginning of another cycle.

In my previously mentioned co-pending application the down motion of the jacks was accomplished by holding the knives temporarily stationary for one pick by means of dwells in the cams. This same dwell of the jacks is accomplished herein by means of the support 126 and the fact that the knives continue to move in the lower part of their range while out of engaging position with the jack for one pick of the loom. I have found that the cranks permit a higher speed of the jacquard than was possible with the cam due in part at least I believe to the fact that the knife motions as set forth herein are continuous instead of intermittent as in my earlier case.

Returning now to Fig. 18 it will be convenient to bear in mind that a punched hole in the card has the same effect on needle 115 as though the card were not in indicating position, such as would be the case if the cylinder were moved out to be operated by the pawl 103, and it is also convenient to remember that after knife 42 has engaged hook 122 when rising the position of hook 123 will be determined independently of the card until knife 42 descends to a point where it can release hook 122. The cylinder and card therefore need not be in indicating position during the interval in which the knife 42 is in engagement with hook 122. Each knife rises during one pick and falls during the next pick, and the outward card feeding and return motions of the cylinder occur during the greater part of two picks or beats of the loom.

Considering first the weave shown in Fig. 10

and assuming that a card is presenting a punched hole 27a to needle 115, a knife 41 will rise to lift hook 121 during the descent of knife 43 and thereby raise terry warp 27 for the laying thereunder of shot 1a. Knife 41 then starts down and a knife 42 starts up without engaging hook 122 so that warp 27 will be down and shot 1b can pass over it. As soon as the normal time for engagement of hook 122 by knife 42 is passed in the ascent of knife 42 the cylinder is moved out by decline 10 113 of cam 90 to be given a quarter turn by the pawl 103.

As knife 42 starts down a knife 43 will start up and will engage hook 123, since the latter is normally positioned over knife 43 by the corresponding spring 131, this condition existing when the card is away from indicating position. Warp 27 therefore is raised again for the passage thereunder of filling shot 1c. This sequence continues so long as unfigured terry warps are to be woven by warp 27 and the latter will form terry tufts on the top surface of the fabric. As many unfigured rows of tufts as are needed will be thus formed, one additional row being provided and formed by unit or group II as shown in Fig. 10.

During the manipulation of warp 27 just described an opposite control will be exercised for terry warp 28. A blank space 28a on all the cards shown in Fig. 17, corresponding to the weave of Fig. 10, controls a needle 114 which positions a second pair of jacks 116 and 117 corresponding respectively to jacks 118 and 119. In the sequence for warp 28 a knife 41 will rise without lifting jack 116, a knife 42 will then lift jack 117 and a knife 43 will then rise without lifting jack 117 despite the fact that the cylinder is out because jack 117 is still hooked on a knife 42. Warp 28 forms the terry tufts on the bottom of the fabric throughout the weave shown in Fig. 10, and a further understanding of the manipulation of warp 28 will be gotten by the description to follow of the manipulation of warp 27 by which the latter is placed in the bottom of the fabric.

At each complete out motion of the cylinder a new card will be placed in controlling position facing the needles. Cards C', C2 shown in Fig. 17 are punched with holes 27a and left blank at 28a to produce the manipulations of warps 27 and 28, respectively, as shown in groups I and II, Fig. 10.

It is assumed that the figured pattern will start at group of shots III, Fig. 10, in which case card C3, Fig. 17, will have that part thereof controlling needle 115 left blank at 27b, and as low point 110 of cam 90 moves the cylinder in to place this card in indicating position, hook 121 will be moved out of the path of knife 41. Knife 41 therefore rises without lifting warp 27 and the latter will be under shot IIIa. During up motion of knife 41, however, knife 43 is descending and in engagement with hook 123 from the previous cycle, and jack 119 is therefore under a strain from needle 115 tending to bend it to the left as viewed in Fig. 18. In order to relieve this bending strain the cylinder is backed off slightly by run 112 of cam 90 as soon as the normal time for engagement of hook 121 by knife 41 during ascent of the latter has been passed. This backing off of the cylinder, which occurs once for each three pick cycle of the loom, is not enough to cause turning of the cylinder by pawl 103. When descending, knife 43 loses control of hook 123 by reason of support 126 before knife 42 rises to a point where it can pick up a jack. Low

point 111 of cam 90 now returns the cylinder and card to the left as viewed in Fig. 3 to give an indication for hook 122 just before the ascending knife 42 reaches a level corresponding to line 5 126a. Fig. 19. Knife 42 will then raise hook 122 and warp 27 will be above shot IIIb. The cylinder is moved all the way out by incline 113 of cam 90 to cause turning by pawl 103 to place the next card in controlling position.

10 Knife 42 now holds both hooks 122 and 123, and as previously described, this will determine the position of hook 123 on the next pick. As knife 43 ascends hook 123 will be held out of its path because hook 122 is on knife 42, and warp 15 27 will therefore be down at the end of the up motion of knife 43 so that shot IIIc can pass over warp 27. This places warp 27 in the bottom shed and its tuft loops will be on the underside of the fabric along with those of warp 28 to 20 form the pattern. As many such cycles are repeated as the pattern demands, units or groups IV and V being shown as similar to group III in Fig. 10.

When the figure is completed, as at group VI, 25 card C6 then in control will present a hole 27a to needle 115, and the relation of warp 27 to the shots VIa and VIb and VIc will be as described in connection with group I. Warp 27 is thereafter restored to the top shed to form tufts on 30 the upper side of the cloth, and the figure, so far as warp 27 is concerned, is completed. An additional card C7 is shown to form group VII which with group VI, continues the weaving of unpattered fabric.

35 Fig. 11 shows the tufting of the fabric woven as indicated in Fig. 10 and suggests that the pattern is formed by the production of a blank space on one side of the cloth, the tufts on the opposite sides of the blanks being of double density. When the pattern is to be formed as suggested in Figs. 10 and 11, therefore, there will be no change in the several cards with respect to their control of the lower tuft forming warp 40 28, and the variation in the punching of the cards will come only with respect to the control exercised by the cards on warp 27.

Turning now to the fabrics set forth in Figs. 8 and 9 it will be seen that warp 25 is controlled in a manner similar to that already described for 45 warp 27. Warp 26 normally forming the bottom tufts, however, is controlled the same as that of warp 25 except in reverse direction, and wherever the cards have a hole punched for the lifting of warp 25 there will be a corresponding blank for lowering the warp 26, inasmuch as these two 50 warps 25 and 26 are always on opposite sides of any given shot of filling. In this instance the pattern is produced by a color change, warp 25 being one color while warp 26 is of a different color, and there will be tuft loops on both sides of the fabric throughout the length of the pattern.

Fig. 16 shows a series of cards which will produce the weaves found in Fig. 8. In these cards 55 it is assumed that the upper left hand corner of each card is reserved for the control of the warp thread which normally provides the top tufts in an unfigured part of the cloth and that the lower left corner controls the warp threads 60 normally forming the bottom tufts. In Fig. 16 card K' corresponds to the group I of weft shots, Fig. 8, and the perforation 25a causes lifting of warp 25 over shot Ia, lowering under shot Ib, and lifting over shot Ic, as did hole 27a for warp 27 65 in the previous description. Cards K', K2, K6

and K7 have punched holes 25a in their upper left corners, while cards K3, K4 and K5 are blank in that corner, these cards being the same in this respect as the corresponding cards of Fig. 17, and therefore causing warp 25 to be like 5 warp 27.

Warp 26 is disposed as is warp 28 in groups I, II, VI and VII and the corresponding cards K', K2, K6 and K7 are therefore blank in their lower left corners, as are cards C', C2, C6 and C7. In 10 the three shot groups III, IV and V, however, warp 26 is disposed oppositely to the arrangement of warp 28 in the corresponding groups of Fig. 10, and therefore where cards C3, C4 and C5 are blank in their lower left corners, cards K3, 15 K4 and K5 are perforated, see Fig. 16, to cause warp 26 to lie under shots b of groups III, IV and V and over shots a and c of these groups. This arrangement of holes and blanks means that the warps 25 and 26 are always on opposite sides 20 of any given shot of filling, a condition already pointed out as essential to the weave shown in Fig. 8.

All three of the cranks 71, 72 and 73 and also 25 cam 90 are capable of rotation in opposite directions, the cam 90 being symmetrical to permit this reversal. Because of this fact the jacquard may be driven either in the sequence already described or in the reverse sequence, the cranks having their settings altered on their driving 30 shafts to produce results similar to those already described.

From the foregoing it will be seen that I have 35 provided a jacquard for a terry loom having three knives each of which rises for one pick, falls for one pick, and has an idle motion for the third pick permitting a one pick dwell of the jacks in low position, and that the three knives have these motions one pick apart so that one knife is always rising on one pick, another is always falling and another is always having the idle motion represented by that part of the graph in Fig. 19 below the line 126a. It will further be seen that the character of motion set forth hereinbefore is derived from three cranks which are equally 40 spaced angularly around a shaft requiring three picks of the loom for a revolution and that the continuous motion caused by the cranks contributes partly at least to the fact that the jacquard equipped with a crank motion for the knives 45 can operate at a high speed.

The broad features of the structure set forth herein are claimed in the previously mentioned co-pending application, while this application is limited to the structural advantages growing out 50 of the continuous drive for the knives such as supplied by the cranks 71, 72 and 73.

Having thus described my invention it will be seen that changes and modifications may be made 55 therein by those skilled in the art without departing from the spirit and scope of the invention and I do not wish to be limited to the details herein disclosed, but what I claim is:

1. In a jacquard mechanism for a loom to weave 60 a terry fabric having successive three pick groups of weft, each group being formed in a cycle and the last weft of one cycle being in the same shed as the first weft of the succeeding cycle and having a warp to be in a given position for the first and third picks of a cycle and in the opposite 65 position for the second pick of the cycle, a card to control the position of the warp for the successive picks of a cycle, three spaced crank arms having a complete revolution for each cycle, and means cooperating with the card and including 70 75

three knives each connected to one of the crank arms, said crank arms to raise said knives one at a time and lift each knife during a pick of the loom to cause said terry warp to be in said given position at the conclusion of the rising of the first and third knives and be in said opposite position at the conclusion of the rising motion of the second knife.

2. In a jacquard mechanism for a loom to weave

- 10 a terry fabric having successive three pick groups of weft, each group being formed in a cycle and the last weft of one cycle being in the same shed as the first weft in the succeeding cycle, and having a warp to be in a given position on one pick 15 of the cycle, in the opposite position on the second pick of the cycle, and again in said given position on the third pick of the cycle, a card to control the position of said terry warp for the three successive picks of a cycle, a shaft having a complete rotation for each cycle, three angularly spaced crank arms secured to and rotating with the shaft, and means cooperating with said card and including three knives each of which is connected to one of the crank arms, the latter to lift one knife for the first pick of the loom and lift the second knife for the second pick of the loom and lift the third knife for the third pick of the loom, any two knives being moved to down position with respect to the means cooperating 30 with the card by the crank arms corresponding thereto when the other knife is in high position, said crank arms and the knives driven thereby causing the warp to be in said given position at the conclusion of the rising motion of the first 35 knife, to be in said opposite position at the conclusion of the rising motion of the second knife, and to be again in said given position at the conclusion of the rising motion of the third knife.

3. In a jacquard mechanism for a loom to

- 40 weave a terry fabric having successive three pick groups of weft, each group being formed in a cycle and the last weft of one cycle being in the same shed as the first weft in the succeeding cycle, and having a warp to be given two weaving positions, three separately movable knives, three crank arms having a complete rotation for each cycle and said crank arms being spaced angularly, connections between the crank arms and the knives to give the latter a cycle of movement to be completed in three picks of the loom and during which cycle each knife rises for one pick of the loom, a card cylinder carrying a card, means to present the cylinder and card to indicating position for every cycle of the loom, 45 and means controlled by the card when in indicating position and actuated by the knives to place said warp in one position at the end of the rising motion of one of the knives and to place the warp in the other position at the end of the 50 rising motion of the second knife and to return the warp to the first position at the end of the rising motion of the third knife.

4. In a terry mechanism for a loom having a

- 65 warp to be in a given position on the first pick of the loom, in the opposite position on the second pick of the loom, and again in the given position on the third pick of the loom, a card to control the position of the terry warp, three angularly spaced crank arms having a complete rotation 70 every third pick of the loom, and means cooperating with the card and including two lifting jacks one with the single hook and the other with a double hook and three independently moving knives, one knife connected to each crank 75 arm, there being one knife for each hook, to place

said warp in said given position when one of the knives has completed its lifting motion and to place said warp in the opposite position when the second knife has completed its rising motion and again place the warp in said given position when the third knife has completed its rising motion.

5. In a jacquard mechanism for a terry loom, three independently movable knives, three angularly spaced crank arms having a complete 10 rotation every third pick of the loom, means to connect each knife with a crank arm so that each of the latter is connected to a knife, said crank arms causing the knives to have a cycle of movements extending through three successive 15 picks of the loom and each knife to be moving up while another knife is descending and a third knife is dwelling in low position, a pair of terry controlling jacks one having one hook for one knife and the other jack having two hooks one 20 for each of the remaining knives, a needle to position the jacks, a card to position the needle, one of the crank arms to move the knife corresponding thereto up for the first pick and in engagement with one of the jacks to elevate the 25 same, the second crank arm to move the knife corresponding thereto up as the first knife descends and out of engagement with any hook to permit the first knife to lower the jack in engagement therewith for the second pick of the 30 loom, and the third crank arm to raise the knife corresponding thereto to engage one of the hooks of the other jack to raise the same for the third pick of the loom, and means by which said jacks 35 jointly control a terry warp thread.

6. In a jacquard mechanism for a loom having a warp to be raised one pick, lowered the next pick and raised the third pick, three lifting hooks for the warp, means to cause the warp to be raised when any hook is lifted, the warp being 40 down when no hook is lifted, three lifting knives, one for each hook, three angularly spaced crank arms having a rotation every third pick of the loom, each knife connected to a crank and the latter lifting the knives in consecutive order 45 during a cycle of three consecutive picks of the loom, said cranks effective to lift a knife for each pick of the loom, a card to control the hooks, means to move the card to controlling position relatively to the hooks every third pick 50 of the loom, and means cooperating with the card and controlling the hooks to place two of the hooks in position to be lifted by the first and third knives to rise during the cycle to raise the warp for the first and third picks of the loom, 55 and said last named means placing the second hook out of the path of the second knife to rise in the cycle and thereby leave said warp in low position for the second pick of the loom.

7. In a jacquard mechanism for a loom having a warp to be raised for the first and third of three successive picks of the loom and to be in low position for the second of said three successive picks, a pair of warp lifting jacks one of which has one hook and the other of which has two 65 hooks, three hook engaging jack lifting knives, three angularly spaced crank arms having a complete rotation every third pick of the loom, each knife being connected to a crank arm and each crank arm connected to a knife, said crank 70 arms to raise one knife and lower the other knife and maintain the third knife in a substantially idle down position during a pick of the loom, the crank arms to raise the knives successively one at a time so that three picks 75

of the loom are required for a complete cycle of operations thereof, means to raise the warp when either jack is lifted, the warp to be down when both jacks are in low position, a needle 5 to determine the position of the jacks with respect to their respective knives, a card to control the position of the needle preparatory to rising of the first and second knives, said cards and means cooperating to place the hook of the first 10 jack out of the path of the first knife when the latter rises and acting to place one of the hooks of the second jack in the path of the second knife when the latter rises, means to move the card away from indicating position with respect to the 15 needle subsequent to engagement by the second knife of the hook therefor, and said second knife and first hook of said second jack cooperating to hold the second hook of said second jack out of the path of the third knife when 20 the latter rises while the card is out of indicating position with respect to the needle.

8. In a jacquard mechanism for a terry loom, three independently movable knives, each having a cycle of movements extending through 25 three successive picks of the loom, three angularly spaced crank arms having a rotation every third pick of the loom, means to connect each knife with a separate crank arm, each crank

arm moving the knife connected thereto up while another crank arm moves the knife connected thereto down and while the third crank arm gives the knife connected thereto an idle motion, a pair of terry warp controlling jacks one having 5 one hook for one knife and the other jack having two hooks one for each of the remaining knives, a support for the jacks to hold the latter in low position when said hooks are out of engagement with the knives and the latter have 10 idle motions, a needle to position the jacks, a card to position the needle, one of said cranks to move the knife corresponding thereto up for the first pick of the loom and in engagement with one of the jacks to elevate the same, the 15 second crank moving the knife connected thereto up as the first knife descends and out of engagement with any hook to permit the knife to lower the jack in engagement therewith to the low position determined by said supporting 20 means for the second pick of the loom, and the third crank to raise the knife corresponding thereto to engage one of the hooks of the other jack to raise the same from the low position determined by said supporting means for the 25 third pick of the loom, and means by which said jacks jointly control a terry warp thread.

HERBERT V. FOSTER.
